FIREPLACE OR THE LIKE

Ray Derringer, Port Edwards, Wis., assignor to Preway Inc.

Filed Sept. 30, 1969, Ser. No. 19,351

Term of patent 14 years

Int. Cl. D23—03

U.S. Cl. D23—97

FIG. 1 is a front perspective view of a fireplace or the like showing my new design;

FIG. 2 is a front elevational view thereof;

FIG. 3 is a side elevational view thereof; and

FIG. 4 is a top plan view thereof.

The side opposite that shown in FIG. 3 is substantially identical to that shown.

The rear of the fireplace is generally flat and plain in appearance.

The fireplace screen or similar closure is shown in broken lines in FIGS. 1 and 2 for illustrative purposes only.

I claim:

The ornamental design for a fireplace or the like, as shown and described.
